UNITED STATES PATENT OFFICE.

LAZARUS MUNTEAN, OF HIGHLAND PARK, MICHIGAN.

RESTAURANT SYSTEM.

1,377,969.

Specification of Letters Patent. Patented May 10, 1921.

Application filed August 19, 1920. Serial No. 404,703.

To all whom it may concern:

Be it known that I, LAZARUS MUNTEAN, a citizen of the United States, residing at Highland Park, in the county of Wayne 5 and State of Michigan, have invented certain new and useful Improvements in Restaurant Systems, of which the following is a specification, reference being had therein to the accompanying drawings.

10 This invention relates to a restaurant system which has been designed along the lines of the well known "cafeteria service" and the primary object of my invention is to provide a continuous service restaurant by 15 which a large number of patrons may be fed in a comparatively short time, the restaurant being especially designed for industrial plants where a large number of workmen must be accommodated within a specified 20 time.

Another object of this invention is to provide a lunch system wherein a movable tramway is equipped with tables for lunch purposes and each table has drinking fountains and other accessories for the convenience of customers seated at the table.

25 A further object of this invention is to provide a compact culinary department wherein cooking ranges, dish washing machines, and other equipment are assembled so that loaded and unloaded dishes may be expeditiously handled and repeatedly used, without any interruption during a rush hour of service.

30 A still further object of this invention is to provide a restaurant which will permit the patrons being served indoors or out doors according to the weather, and provision is made for continuously carrying the patrons about the restaurant to permit of repeated self-serving or exit when desired.

35 The above and other objects are attained by a novel constructive arrangement of parts that will be hereinafter more fully described 40 and then claimed.

Reference will now be had to the drawings, wherein—

Figure 1 is a diagrammatic view in plan of a restaurant service in accordance with 45 this invention;

Fig. 2 is a plan of a portion of a table train, and

Fig. 3 is a side elevation of the same.

A restaurant in accordance with my invention includes a suitable building having 50 a large room defined by a front wall 1, a

rear wall 2, and a side wall 3. Between these walls are various partitions to provide compartments for different purposes. For instance, the side wall 3 has a partition 4 parallel to the front wall 1 to form a room 5 and this room contains sinks 6 and other equipment. At the open end of the room there is a series of sinks 7 that may be used for various purposes.

60 Adjacent the wall 2 are partitions 8 providing a store room 9, a meat room 10, a pantry 11, and an ice box 12, said ice box serving the rooms 9, 10 and 11. These rooms open into a large passage-way 13 equipped with work tables 14, a meat block 15 and cooking ranges 16 adjacent said meat block.

65 Before considering the rest of the culinary department reference will be had to an endless tramway by which patrons are carried about the greater part of the restaurant. Adjacent the front wall 1 is an entrance platform 17 connected to a loading platform 18 and an unloading platform 19 by bridges 20 and 21. Additional unloading 70 platforms 22 are provided to take care of a large crowd.

75 Extending under the bridges 20 and 21 is the outer loop portion 23 of an endless track which extends along the outside of the building and around the walls 2, 3 and 1 to a loop portion 24 on an exit platform 25 and this particular loop portion is spanned by a bridge 26. The track returns the same 80 way to the loading platform 18 and has an inner loop portion 27 about the unloading platform 22 within the outer loop portion 23. The track again returns to the exit platform 25 to provide another loop portion 28 spanned by a bridge 29 and the loop portions 24 and 28 are substantially parallel, while the loop portions 27 and 23 are practically one within the other, thus providing 85 a four track system about the culinary department.

90 On the endless track are placed trains, each composed of a plurality of coupled cars or platforms 30 supported by trucks 31 on the endless track. One or more of the cars of each train may be provided with electric motors 32 having suitable power transmission mechanism so that the motor equipped car may be driven and thus pull or push the train in the direction of the arrows shown in Fig. 1. The motors 32 may 95 receive electrical energy from storage batteries on one or more of the cars or said mo-

tors may be operated from a trolley or third rail system suitably controlled by the manager of the restaurant.

On each car or platform 30 is a pedestal 5 table 33 and chairs 34 or suitable seats for patrons. Each table has a lighting fixture 35 and a motor 36 for operating a fan 37, said motor being supplied from the same source of electrical energy as the motors 32. 10 In addition to the lighting fixtures 35 there are other fixtures, including condiment holders 38 and pivoted drinking fountains 39, said drinking fountains having connections 40 through the table pedestals to a 15 train line 41 having hose connections 42 between the coupled cars of the train. The train line 41 communicates with a conventional form of pump 43 driven from an electric motor 44 operated from a suitable source 20 of power, and the pump 43 communicates with a reservoir 45 suitably suspended beneath the pump equipped car of the train. From time to time the reservoir 45 may be supplied with drinking water and the water 25 forcibly supplied to the drinking fountains of the tables.

Again considering the culinary department that portion of the track adjacent the large room extends between endless dish 30 conveyers 46 on which dishes are placed so as to be within easy reach of patrons on the slowly moving trains and as each train passes between the dish conveyers a patron 35 may select a desired wish. The dish conveyers are served from steam tables 47 and milk and coffee urns 48 with attendants near by to replenish the dish conveyers.

At one end of the dish conveyers is a food 40 conveyer 49 which passes under the track and permits of food being easily and quickly conveyed to the different steam tables or to the dish conveyer, so that as fast as the patrons occupy the tables and pass between the dish conveyers the patrons have a self- 45 service and may consume the food while being carried around to the loop portion 24. If the lunch or meal has been of short duration the patron may leave the train at the exit platform 25, or otherwise be carried to 50 the starting point where the patron may leave at the unloading platform 22 within the loop portion 27. Should the patron care to continue the train proceeds to the loop portion 28, where the patron may leave the 55 train or continue to the unloading platform 22 outside of the outer loop 23.

In order that used dishes may be removed from the tables, endless dish conveyers 50 are located adjacent the large or outer loop 60 23 and the used dishes are conveyed to dish washing machines 51 and then to dish shelves 52, both of which are compactly arranged in the building.

Cashier booths 53 are located at the rear 65 ends of the dish conveyers 46 and as the

patrons pass between these booths the selected food is paid for.

With short trains or articulated trains slowly and constantly moving past the loading and unloading platforms, it is apparent 70 that a large number of patrons may be accommodated at the tables and it is only necessary for a patron to watch for a vacant seat to be insured of prompt service. It is apparent that the trackage of the system 75 may be increased and sufficient trains provided to permit of a large number of people being fed in a comparatively short time and the building may be constructed with the endless tracks in the open or inclosed. In 80 some instances, for instance, at a State fair, a building is not necessary as a tent may be used.

In order that small meals or "short orders" 85 may be expeditiously taken care of in the restaurant, I arrange stoves or ranges 54 adjacent the dish conveyers and steam tables, and dishes may be partly prepared in the main kitchen and then finished at the stoves or ranges 54. Patrons entering the restaurant 90 may observe menus at the loading platforms and give orders for meals. These orders may be sent to the main or auxiliary kitchens by suitable signals so that the orders will be under way by the time the 95 patrons reach the dish conveyers. As a matter of fact, suitable signals and electrically operated stairways may be used throughout the restaurant, and while in the drawings there is illustrated a preferred embodiment of my invention, it is to be understood that the specific arrangement of the endless track, the culinary equipment, etc., 100 may be changed without departing from the scope of the appended claims.

What I claim is:—

1. An endless track for a restaurant providing a substantially rectangular inclosure and having parallel loop portions at one side of the inclosure and loop portions one 110 within the other, at another side of the inclosure, said loop portions affording a gap as an entrance to the inclosure, and table carrying cars on said track.

2. An endless track as characterized in 115 claim 1 and unloading platforms located inside and outside the track, loop portions at one side of the inclosure and loading and unloading platforms located inside and outside the other loop portions of the track.

3. A continuous track as characterized in 120 claim 1 and a bridge spanning each of the loop portions of the track.

4. An endless restaurant system comprising 125 trains of cars adapted to be constantly moved, tables on the cars, drinking fountains having water supply connections extending upwardly through each table, a source of water supply for the fountains of all of said tables, and means operated by the 130

train of cars in motion for forcibly supplying the water to the drinking fountains.

5. A restaurant comprising a culinary department providing self-service at one side of said culinary department, an endless track providing a square or inclosure for the greater part of said restaurant and extending past the self-service, said track having loop ends spaced apart affording entrance to 10 the culinary department, and cars adapted

to constantly move on the track and permit of patrons reaching self service at the restaurant.

In testimony whereof I affix my signature in presence of two witnesses.

LAZARUS MUNTEAN.
